UNITED STATES PATENT OFFICE.

HERBERT WESTCOTT, OF SOUTH HAMPSTEAD, LONDON, AND ARTHUR JOSHUA TETLEY,
OF BEDFORD, ENGLAND.

PORTABLE LOCK-STITCH SEWING-MACHINE.

1,200,675.

Specification of Letters Patent.

Patented Oct. 10, 1916.

Application filed January 21, 1915. Serial No. 3,582.

To all whom it may concern:

Be it known that we, HERBERT WESTCOTT and ARTHUR JOSHUA TETLEY, subjects of the King of Great Britain and Ireland, residing, respectively, at 21 Adelaide road, South Hampstead, London, N. W., England, and Hilbre Grange, Bedford, in the county of Bedfordshire, England, have invented new and useful Improvements in Portable Lock-Stitch Sewing-Machines, of which the following is a specification.

This invention relates to a portable lock stitch sewing machine and consists of the formation and combination of parts to make the machine hereinafter described a lock stitch sewing machine, cheap in construction and portable.

In order that this invention may be the better understood drawings are shown hereinafter with of a machine built in accordance with this invention.

Figure 1 is an elevation of the machine. Fig. 2 is a plan on the line 2—2 of Fig. 1 with the working table removed. Fig. 3 is an end elevation on the line 3—3 of Fig. 1 the gear wheels being removed. Fig. 4 is an end elevation of the details of the under feed mechanism.

A general metal frame *a* is made in the shape of the letter G with the usual hand wheel *b* on a shaft geared into a top driving shaft *c* so as to produce the operation of the needle *d* there being a metal work table *e* above the under side *f* of the frame. Upon this under side *f* is provided a screwed stud *g* forming the fulcrum of an under lever *h*. This under lever *h* is rocked horizontally by another back lever *i* which has a fulcrum at *j* and is operated by the cam *k* upon the upper driving shaft *c* which works in a fork *l* at the upper end of the back lever *i*.

The farther end *h'* of the under lever *h* engages by a slot gearing onto a pin with the framework or shuttle-carriage *l*, carrying a shuttle *m* having the under thread, and moves this framework or shuttle carriage *l* backward and forward in a straight line upon a fixed pin *n* at right angles to the line of the upper driving shaft *c*.

The movement of the cloth through the machine is effected by an under feed *n* pressing upward against a presser foot *o* operated downward by a spring *o'* in the needle bar holder *p*.

The framework or shuttle carriage *l* holds

ing the shuttle or spool *m* is fitted with a pin or screw *q* that comes forward through the framing to operate the under feed *n*. At high velocities this feed apparatus as hereinabove described is the most simple, there being no disconnected pins to make engagement with projections on other parts. Further this arrangement is not noisy at high velocities. Upon this pin or screw *q* is a lever *r* that oscillates a disk *r'* backward and forward upon a fulcrum *s*. Upon this fulcrum *s* and loosely fitting thereon is fitted a triangular piece *s'* which has attached to it a three tooth ratchet *t* operated by a spring pressed pawl *t'* fitted to the disk *r'* so that as the disk *r'* rotates, the triangular piece *s'* by the pawl *t'* and ratchet *t* also rotates, so as to lift up the under feed *n*, to press upward upon the presser foot *o*. There is also a cam face *u* fitted to the disk *r'* so that when the under feed *n* is lifted up it is thrust forward by the downward projection *n'* fixed to the feed *n* against the spring *w* to effect the feed. When the cam face *u* has passed from the projection *n'* the feed *n* is brought back by the spring *w* until its end strikes against the end of set screw *w'* which determines the length of the feed.

To give the proper amount of slackness to the upper thread, so that it may extend to allow the shuttle to pass through its bight, the upper thread passes through the eye of a take up lever.

The usual top bobbin with thread adjustment to the needle, the means for operating the needle, and the usual shuttle bobbin winder *z* are provided in this machine.

We claim:

A lock stitch sewing machine comprising a driving shaft, a frame, a shuttle framework carrying the shuttle and under thread adapted to have a straight reciprocating motion, a bar at right angles to the line of the driving shaft adapted to carry the said shuttle framework, a horizontally reciprocating under lever adapted to have motion in one plane only and operate the said shuttle framework, a back lever rocking in a vertical plane about a fixed axis adapted to operate said under lever, a cam mounted on the driving shaft and adapted to operate said back lever, a disk pivoted upon a pin and rocked by a lever connected to the shuttle framework, a triangular piece pivoted upon the same pin as the said disk, a three-

tooth ratchet wheel firmly affixed to the said triangular piece a spring pressed ratchet pawl pivoted on the said disk, and adapted to engage said ratchet wheel so that when the said disk is rocked the said triangular piece is turned in one direction only so as to press up the under feed at each alternate stroke of the said disk and a cam piece upon the said disk, adapted to move the said under feed longitudinally, the combined effect of the said triangular piece and the said cam piece being to produce an under feed which

will operate with a forward motion, when in the raised position and a backward motion when in the lowered position.
